UNITED STATES PATENT OFFICE.

KENNETH S. JOHNSON, OF JERSEY CITY, NEW JERSEY, ASSIGNOR TO WESTERN ELECTRIC COMPANY, INCORPORATED, OF NEW YORK, N. Y., A CORPORATION OF NEW YORK.

TRANSMISSION SYSTEM.

Application filed July 1, 1918. Serial No. 242,797.

To all whom it may concern.

Be it known that I, KENNETH S. JOHNSON, a citizen of the United States, residing at Jersey City, in the county of Hudson, State 5 of New Jersey, have invented certain new and useful Improvements in Transmission Systems, of which the following is a full, clear, concise, and exact description.

This invention relates to transmission systems, more particularly it relates to means for improving the quality of transmission from an incoming line to a vacuum tube repeater.

It is well known in the art of telephony, 15 that the proper functioning of a transmission system depends, to a great extent, on the relative proportioning of the electrical impedances of the component elements of the system. Thus it has been found that the 20 voltage impressed by a transformer from an incoming line on a repeater varies considerably with the frequency, thereby impairing the quality. In accordance with this invention, it has been found that the quality 25 of transmission in such a circuit may be considerably improved by shunting an impedance across the input side of the transformer. On a one-way repeater circuit the 30 value of the impedance may be varied between considerable limits, although in general, a resistance of the order of the effective 35 resistance of the line has been found quite satisfactory. In two-way repeater circuits where accurate balancing between the lines 40 and the artificial networks is required, the value of the impedance across the input side 45 of the transformers should be equal to one-half the impedance of the incoming line. That this value should hold for two way 50 repeater circuits will be apparent from the detailed description of this invention.

Previous to this invention it has been known that the quality of transmission could be improved by connecting across the terminals of the secondary winding of the input 55 transformer a resistance equal to the value of the effective resistance of the line multiplied by the square of the ratio of turns of the transformer, but such an arrangement necessitates the use of a very high and more costly resistance compared with that employed in this invention. For good repeater operation, it is also preferable to have as little apparatus as possible associated with 60 the input circuit of a repeater, because of

capacity effects that might result therefrom, which would cause a substantial short circuit between the input electrodes of the repeater and a lowering of its efficiency.

It has been found that there is also less 60 energy lost in the input transformer when the resistance is on the input side and also less liability for cross-talk between neighboring repeater circuits. Experiment has furthermore shown that a greater amplifica- 65 tion may be obtained from a repeater having the resistance across the input side rather than the output side of the transformer.

This invention will be better understood 70 by reference to the detailed description of the drawings, in which Figure 1 shows this invention in connection with an incoming line inductively associated with a vacuum tube repeater for one-way operation, while 75 Figure 2 shows this invention in connection with a two-way repeater circuit.

Referring to the drawing, 3 is an incoming line which terminates in the primary 80 winding 4 of a transformer 5, the secondary 6 of which is connected between the grid 7 and cathode 8 of a vacuum tube repeater 9. Signals impressed upon the input circuit of the tube 9 by the line 3 are therefore 85 reproduced in amplified form in the output circuit of the tube and the amplified signals may be impressed upon an outgoing line 10 by a transformer 11.

In order to prevent the voltage impressed 90 by the transformer 5 on the amplifier 9 from varying with the frequency, it is desirable to insert a resistance 12 in shunt to the primary winding. From a quality stand-point the smaller the value of this resistance 95 the better the quality, but it is apparent that making the resistance very small would improve the quality only at considerable expense to the transmission efficiency of the system.

In general it will be found that for transmission lines a value of the resistance 12 of the order of the effective resistance of the incoming line will be quite satisfactory.

In Figure 2, 15 is a vacuum tube for repeating signals from the line 16 to the line 105 17, while 18 is a vacuum tube for repeating signals in the opposite direction. 19 is an artificial network for simulating the impedance of the line 16 and should have an impedance equal to the impedance of the line. 110

Similarly the network 20 should simulate the impedance of the line 17. In accordance with this invention the impedance of the circuit at the point 23 should be the same looking in either direction, and since the incoming circuit for the transformer comprises in parallel the line 16 and the artificial line 19, the effective resistance at the terminals 23 looking in the direction of the incoming circuit is one-half the effective resistance of the line 16. The value of the resistance 26 should then be equal to one-half the resistance of the line 16. Similarly, resistance 28 across the primary winding 29 should equal one-half the effective resistance of line 17. With such values for resistances 26 and 28, the balance conditions necessary for no local circulation of power in the repeater station are obtained.

20 The resistances 26 and 28 will in some cases provide a sufficiently accurate simulation of the impedance of lines 16 and 17. In case that these lines have an appreciable amount of reactance as well as resistance, 25 the reactance component of the impedance may be simulated by reactances such as condensers 30 and 31 in shunt to the resistances 26 and 28 respectively. The circuit or mesh provided by resistance 26 and condenser 30, 30 and by resistance 28 and condenser 31 is commonly called a network or artificial line.

Although this invention has been described above in connection with circuits employing vacuum tube repeaters, it is evident that it is also applicable to circuits in which other types of repeaters such as mechanical repeaters are employed.

It is obvious that the principles above set forth may be embodied in systems widely different from that described herein without departing from the spirit of the invention as defined in the appended claims.

What is claimed is:

1. In combination, an incoming line, a 45 translating device, a transformer having a primary winding connected with said line and a secondary winding connected with said device, and an impedance connected to the primary side of said transformer and having an impedance closely approximating the effective impedance of said line.

2. In combination, an incoming line, a transformer having its primary winding connected with said line, a repeater for said line connected with the secondary winding of said transformer, and a resistance element connected in shunt to the terminals of said primary winding for improving the quality of transmission from said line to said repeater, said element having a resistance closely approximating the resistance of said incoming line.

3. The combination with an incoming circuit, of a transformer having its primary

connected to said line, a vacuum tube associated with the secondary winding of said transformer, and a resistance connected across the terminals of said primary, said resistance having a value closely approximating the resistance of said circuit.

4. A two-way repeater circuit comprising an actual line, an artificial line and a circuit connected between said lines comprising a transformer, an artificial line connected at the primary of said transformer, and a repeater connected to the secondary of said transformer.

5. A two-way repeating system comprising an incoming line, an outgoing line, a uni-directional path for repeating between 80 said line comprising an amplifying element, a transformer for connecting said element to said incoming line, and an impedance connected in shunt to the primary of said transformer, said impedance having a value 85 closely approximating one-half of the impedance of said incoming line.

6. A two-way repeater circuit comprising two lines, a vacuum tube for repeating signals from one of said lines to the other 90 of said lines, a second vacuum tube for repeating in the opposite direction, a transformer connecting the input of each of said repeaters with one of said lines, and an artificial network in shunt to the primary 95 of each of said transformers.

7. In combination, an incoming line, a translating device, a transformer having a primary winding connected with said line and a secondary winding connected with 100 said device, and an impedance in shunt to said primary winding, said impedance having such a value that the impedance between the points across said line adjacent said impedance, looking in the direction of said impedance and said transformer, closely approximates the impedance looking from said points in the direction of said incoming line.

8. A two-way repeating system comprising two line sections, a balancing network 110 for each of said line sections, a uni-directional path for repeating in one direction between said lines, a second uni-directional path for repeating in the opposite direction between said lines, each of said paths comprising a vacuum tube amplifier, a transformer for coupling said amplifier to one of said lines, and a resistance element in shunt to the primary winding of said transformer for causing the voltage impressed 115 on the amplifier to be substantially constant over a wide range of frequencies, said resistance having a value closely approximating the resistance of one of said lines and its balancing network connected in parallel. 120

In witness whereof, I hereunto subscribe my name this 24th day of June A. D., 1918.
KENNETH S. JOHNSON.
